H. D. BRANDT

NECKTIE PRESS

Filed Nov. 2, 1926

Inventor:
Harrison D. Brandt,

By Richard E. Babcock
Atty.

UNITED STATES PATENT OFFICE.

HARRISON D. BRANDT, OF SHARON HILL, PENNSYLVANIA.

NECKTIE PRESS.

Application filed November 2, 1926. Serial No. 145,827.

This invention relates to neck-tie presses and hangers or racks, more particularly to such presses and holders or racks of the type illustrated in my Patent No. 1,547,783 granted July 28, 1925, and has for its primary object to increase the ease and convenience of arrangement of ties in, and removal from, the press and to generally promote the convenience and facility of use of such devices; 10 to provide a simple means for positively holding the pressing leaves or members parallel to the supporting member and for positively releasing it therefrom automatically and simultaneously with the release of the 15 pressing members; and to otherwise simplify and improve the construction of such devices, all as hereinafter set forth, described and claimed.

In the accompanying drawing, in which I 20 have shown merely the preferred embodiment simply by way of illustration of the practice of the invention, as by law required, and with no intention of being understood as limited to the particular embodiment 25 illustrated, but on the contrary well recognizing that said invention may be embodied in a number of other and different forms:

Figure 1 represents a front view of a device embodying my invention, open; 30 Figure 2, an end view thereof, closed; with a tie H shown therein; Figure 3, a top plan view thereof, closed; Figure 4, an enlarged, detail, fragmentary view of the opening end of the device, released and slightly swung open, with a tie H shown therein hung on leaf D; 35 Figure 5, a detail central longitudinal sectional view on the same scale as Figure 4 and through the same portions shown therein 40 of the leaves A and D;

Figure 6, a cross-sectional view on the line 6—6 of Figure 5, looking in the direction of the arrows;

Figure 7, a fragmentary top plan view 45 with the leaves A and D spread, upper lug I partially broken away and upper bar I omitted to show details of hinge connection; and

Figure 8, a detail, fragmentary, longitudinal sectional view through the hinge end of leaf D showing the pivot rod 3 in bead 9 thereof.

Referring now in detail to the drawings, A designates a supporting leaf or member 50 having lugs B formed with key-hole slots C extending in a vertical direction from the

top and bottom edges of each end portion of, and preferably in the same plane as the rear face of, said leaf A to constitute two pairs of suspending lugs so that the device 60 may be suspended to open either from the right or left and will lie flat against the supporting medium.

Two hinge lugs 1 constituting a pair of hinge members extend horizontally from the front face of leaf or member A to receive between them the legs 2^a of a hinge bail having a bar 2 connecting said legs, a long rivet pivot pin 3 passing through said lugs 1 respectively and having its intervening portion lying in the bead 9 of the corresponding guideway or chamber 4 to thus constitute a pivotally hinged connection between the supporting member or leaf A and the pressing members D and E. The cross- 75 bar 2 of said bail passes in cooperating guideway or chamber 4 transversely across the hinged end of said leaf D to hold between it and the opposed face of said leaf D, and under compression, two helical springs 5, 80 said cross-bar 2 and rear portion of said leaf D being provided with suitable opposed registering spring positioning points 6 which may be punched up from the metal of the respective parts. 85

The legs 2^a of said bail 2 are directed forwardly and straddle said leaf D and also leaf E and are connected to each other and pivotally to the intervening leaf E in their front end portions by means of a long rivet 90 pin, such as 7, passing through the forward end portions of said legs 2^a and the intervening side edge flanges or bracing ribs F of leaf E.

The ends of the chambers or guide-ways 4 95 are open, as illustrated in Figures 4, 5 and 6, to allow the springs 5 to be compressed, and to expand, according to whether the leaves are closed or open.

By the construction thus far described it 100 will be seen that there are three leaves all hingedly connected at one end, two of said leaves being pressing leaves and having resilient means interposed in the hinge connection between them for forcing their opposed faces together to exert a definite pressing action.

The other end of the supporting leaf A is provided with a spring catch or locking tongue 8 and the chamber or guide-way 4 110 on the corresponding or swinging end of leaf D will have an additional bead 9 formed

with a slot 10 in its rear and side face in registry with the tongue 8 of the leaf A to normally receive the said tongue 8 when said leaf D is pressed toward leaf A with sufficient force to spring the tongue 8 toward the hinge end of leaf A to ride over the adjacent curved or inclined face of the bead 9 until it reaches the slot 10, when it will spring into the latter and lock the leaves A and D in parallel closed relation until freed.

In order to clamp the pressing leaves D and E together to press a tie or a number of ties a clamping element having a rib-braced cross-bar 11 and legs 12 is pivotally connected to the leaf D by means of a pivot or rivet pin 7 passing through the chamber 4 on the swinging end of said leaf D and has a flat strap 13 provided with centering points 6 interposed between it and the helical springs 5 in said chamber, said strap 13 having notched ends to straddle said pin to position said strap.

The said legs 12 of said clamping element are formed with prying cams 14 as shown in Figure 3, so that as said clamping element is turned to the position shown in Figure 4 to release pressing leaf E so that it may be moved with relation to its cooperating pressing leaf D, said cams 14 will bear against said leaf A with increasing pressure to pry it away from leaf D so as to release the leaf D from locking tongue or catch 8, so that it is practicable to have a very stiff strong tongue 8 so that when the parts are once locked together they will be held against any relative movement such as would give rise to any rattle and are not liable to be jarred apart or swing back and forth with objectionable noise or irritating periodical rattle or banging, but may be so tightly locked together as to be very difficult to release by any attemptad pulling apart by hand etc., and yet may be released with the utmost ease by merely moving the clamping element as necessary to release the leaf E so as to permit it to be moved with relation to leaf D.

The opposed faces of the leaves D and E will each be provided with a slightly yielding layer of material G, preferably felt, as shown.

The legs 2^a of the bail 2 and legs 12 of said clamping element will preferably be equal in length throughout, as shown, and of such length as to cause the compression of the springs 5 when said legs extend at right angles to leaf D and straddle leaf E, and in any event are to be of such length that they will cooperate with their respective springs 5 so as to cause a substantially uniform pressing action throughout the area of the opposed faces of the layers G of the pressing leaves D and E.

To remove or insert a tie, assuming the device to be mounted on a vertically ex-

tending support such as a room or closet door, wall or the like, and that the pressing leaves are clamped together and, as so relatively held, locked to the supporting leaf A, the clamping element will be swung about the pivot pin 7 so as to free the swinging end of leaf E, when the helical springs 5 in expanding will cause relative swinging opening movement between said leaves D and E also the pivotal movement of the clamping member will cause the cams 14 to pry the leaf D away from leaf A, so freeing leaf D from the resilient locking tongue or catch 8, so that the leaves D and E may be swung to positions such as indicated in Figure 1, or intermediate spaced positions such that ties may be easily slipped over the end of leaf D quickly and with the greatest ease, so that, as thus opened, the device permits the use of leaf D as a tie rack on which ties may be hung or from which a tie may be selected as desired.

The device will preferably be normally closed to press the ties therein except when ties are being inserted therein or removed therefrom so that after a tie is hung over leaf D care should be used to see that it is reasonably flat and straight before the press is clamped closed.

In the embodiment illustrated I have provided wire rods or racks I supported upon the upper and lower sides respectively of the leaf D as shown in Figures 1, 2, 3 and 4 so as to support the ties out of contact with the edge of leaf D and facilitate their handling.

The ties will preferably be so arranged that the part which normally forms the slip-knot will lie between the leaves D and E and will be pressed thereby when the said leaves D and E are clamped together, and the other end portion of the ties will extend down freely in the space between the leaves D and A.

However, if it be desired to press two end portions of the same tie at the same time, this may be done by threading the tie through between the upper bar I and the upper edge of the leaf D and bringing both ends down between the pressing leaves D and E.

The leaves D and E will preferably be of sheet metal and preferably will have reinforcing edge ribs or flanges extending at right angles to, and away from, their operative pressing faces respectively, and leaf A may be of wood having its end portions metal shod, bound, or faced, as with sheet metal crimped on, or otherwise held thereto in any suitable manner, as illustrated, said metal facing or part carrying or providing the lugs B, the hinge lugs 1, and the locking tongue or catch 8 respectively, though it is not important that said leaf A have any wooden portion, nor is there any objection

to its being all of a single piece of sheet metal with said suspending lugs, hinge lugs and locking tongue or catch stamped up therefrom.

5 Having thus described my invention, what I claim as new and desire to secure by Letters Patent is:

1. A tie press comprising a supporting member, a hanger and presser leaf pivotally mounted thereon, and a presser leaf mounted to cooperate with said hanger and presser leaf and to have movement with relation thereto, in combination with interengaging locking means carried by said supporting member and said hanger and presser leaf to lock the latter parallel to, and adjacent to, said supporting member, and releasable movable means for holding said presser leaf and said presser leaf and holder in tight contact, 20 said releasable means being formed with portions adapted to pry said hanger and presser leaf away from said supporting element to disengage said locking means during the movement of said movable means to release said presser leaf and said holder and presser leaf therefrom.

2. A tie press comprising a supporting member, a hanger and presser leaf pivotally mounted thereon, and a presser leaf mounted to cooperate with said hanger and presser leaf and to have movement with relation thereto, in combination with interengaging locking means carried by said supporting member and said hanger and presser leaf to lock the latter parallel to, and adjacent to, said supporting member, and clamping means carried by said hanger and presser leaf for clamping said presser leaf tightly to said hanger and presser leaf, said clamping means being movable to release said presser leaf

and being formed with a cam adapted to exert increasing pressure against said supporting member to pry said hanger and presser leaf therefrom to disengage said locking means during the movement of said 45 clamping means necessary to release said presser leaf therefrom.

3. A tie press comprising a supporting leaf, a presser and hanger leaf having a guide on its face opposed to said supporting leaf, and a presser leaf, in combination with a hinge-bail member having its legs straddling said presser leaf and pivotally connected thereto and straddling said presser and hanger leaf and having its bar extending across said hanger and presser leaf and lying in the guide thereon, hinge members extending from said supporting leaf, means extending through said hinge members and an intervening part of said guide to pivotally connect said supporting leaf and said hanger and presser leaf, and resilient means interposed between the bar of said bail member and the opposed face of said hanger and presser leaf to draw the forwardly presented ends of the legs of said bail, and the presser leaf pivotally and hingedly carried thereon, toward the opposed face of said hanger and presser leaf, whereby the adjacent end portions of said three leaves will be 70 hingedly connected and said resilient means will be compressed as said presser leaf is swung toward said hanger and presser leaf to exert a pressure on a tie or ties that may be inserted between said presser leaf and 75 said hanger and presser leaf.

In testimony whereof, I have signed my name to this specification at Sharon Hill, Pennsylvania, this 6th day of October, 1926.

HARRISON D. BRANDT.
